Nelson W. Howard

UNITED STATES PATENT OFFICE.

LOUIS A. CASGRAIN, OF BEVERLY, MASSACHUSETTS, ASSIGNOR TO UNITED SHOE MACHINERY CORPORATION, OF PATERSON, NEW JERSEY, A CORPORATION OF NEW JERSEY.

GRINDING MACHINE.

1,410,551.

Specification of Letters Patent. Patented Mar. 28, 1922.

Continuation of application No. 143,707, filed January 22, 1917, of parts common to both applications. This application filed May 28, 1919. Serial No. 300,255.

To all whom it may concern:

Be it known that I, LOUIS A. CASGRAIN, a citizen of the United States, residing at Beverly, in the county of Essex, and State 5 of Massachusetts, have invented certain Improvements in Grinding Machines, of which the following description, in connection with the accompanying drawings, is a specification, like reference characters on the drawings indicating like parts in the several figures.

This invention relates to grinding machines and more particularly to a machine designed for grinding curved blades having 15 curved edges. The present application is a continuation of application for United States Letters Patent Serial No. 143,707, filed January 22, 1917, as to all subject-matter that is common to the two applications.

20 In a machine for grinding knife blades of the type specified, it is important that the blade shall be so supported with relation to the grinding wheel that the exact bevel and shape of edge desired may be obtained. To 25 this end the general object of this invention is to provide a simple construction of grinding machine adapted for grinding blades with curved edges and so arranged that a blade may be manually moved in a 30 definite path relatively to the grinding wheel.

As a feature of the invention I provide a plurality of extended rests over which a blade may be moved in grinding and the 35 edge thereof maintained at a definite bevel.

Another feature of the invention consists in novel means for determining the form of the edge of the blade, this means including a templet fixed to the blade and a guide for 40 co-operation with the templet.

In the embodiment of my invention exemplified herein I employ a clamp or carrier for holding a templet and the blade to be ground in proper relation to each other to 45 ensure accurate grinding of the blade. A further feature of my present invention resides in the provision of a gage carried by the clamp, said gage being constructed and arranged to determine the proper position of 50 the blade and the templet relatively to each other and to the body of the clamp or holder.

Other features of the invention will appear from a consideration of the appended

claims in connection with the following specification and the accompanying drawings illustrating a preferred embodiment thereof, in which,—

Fig. 1 is a perspective view of so much of my novel grinding machine as is necessary to an understanding of my invention;

Fig. 2 is a side view of the blade guiding mechanism showing a blade and templet and the clamp thereof in section; and

Fig. 3 is a perspective view of one form of clamping device and gage for holding the templet in the desired relation to a blade to be ground.

Journalized in the base 10 is a shaft carrying a grinding wheel 14 which is partially covered in the customary manner by means 70 of a guard 16, one portion 18 of which is pivoted to permit access to the wheel. Fixed and loose pulleys 20 provide means for driving the shaft and wheel. A suitable water receptacle is usually provided to supply water to the wheel by means of a flexible tube 26. A pan 30 is provided beneath the wheel to catch the drippings. This pan may be mounted adjustably with relation to the base by means of a dove-tail groove 32 80 co-operating with a similarly shaped projection on the pan and may be adjusted by means of a hand screw 34 threaded in a lug 36 upon the base.

Secured to this water pan is a bracket 40 85 which acts as a support for an arm 42 pivotally attached thereto. A spring 44 attached to a projection on the bracket 40 and to the arm 42 serves to hold the latter with its attached parts in operative position (as 90 shown) against the hub of the casing 16 or in inoperative position against the pan 30 when it is desired to use the grinding wheel without a guide. The arm 42 is designed with a horizontal portion 43 which enables 95 adjustment thereof, with the water pan, without changing the height of the arm relative to the grinding wheel. Carried upon the arm 42 is a curved guide 46 which is held in comparatively close relation to the grinding wheel and is adapted to act as a rest or support for the upper end of the blade to be ground. This guide is given a curvature which approximates but is preferably sharper than the curvature of the blades to 105 be ground. A rest 48 is provided, for sup-

porting and guiding the lower end of the blade, which rest comprises a curved rod whose lateral arms extend through lugs 50 upon the arms 42 and are adjustably positioned therein by means of set screws 52. The guide 46 and rest 48 therefore constitute two points of support for the knife blade and by proper adjustment of the rest 48 the bevel at which the knife edge will be ground 10 may be exactly determined. Adjustment of the support 40 by manipulation of the screw 34 enables compensation for the varying size of the grinding wheel as the latter wears away during use.

15 A templet 54 is provided which preferably has a cross-sectional contour corresponding to that of the blade to be ground. This templet may conveniently be formed of an old knife blade and will be ground 20 so that its forward end has a shape corresponding to the desired curvature of the edge of the blade. This templet 54 is intended to be clamped upon the outside of the knife blade 56 by means of a clamp 58. One 25 construction of such a clamp is illustrated in Fig. 3 and will be seen to comprise two pivotally joined clamping members with hooked ends, one of these members being provided with a tapped extension 60 adapted to 30 receive a thumb-screw 62 for forcing the hooked end into engagement with the lateral edges of both the templet and the knife blade. Ears 76 upon the clamp members 58 serve to contact with the outer sides of the 35 guide 46 to limit the lateral movement of the blade with respect to the grinding wheel.

Associated with this templet is a templet 40 guide 64 formed as a circular disc pivotally mounted upon a bracket 66 which is pivotally attached at 68 to an extension of the arm 42. This extension 70 may conveniently be formed integrally with the guide 46 but obviously such a construction is not essential. Movement of the bracket 66 relative to the extension 70 is limited by means of bolts 72 passing through ears on the bracket 66 and on the extension 70 in order to facilitate the insertion of a blade for grinding. A spring 74 is joined to the extension 70 and the bracket 66 and tends to move the templet guide 64 toward the guide 46 and the rest 48 at a point between these guides.

55 If the rest 48 has been properly adjusted relative to the guide 46, a blade and templet when clamped together may be rested upon the guide and rest and the support 40 adjusted to bring the blade in contact with the grinding wheel by manipulation of the screw 34. The rotatable templet guide 64 will then bear upon the outer face of the knife blade and form an abutment against which the edge of the templet may be 60 pressed thereby to guide the blade so that

its edge will be ground with the desired curvature. This guide 64 will also serve to hold the blade against the guide rests 46 and 48. As the blade is moved by hand over the guide 46 and the rest 48, lateral movement 70 of the blade may conveniently be limited by the engagement of ears 76 of clamp 58, with the outer sides of the guide 46, to insure that it shall not be moved past the edge 75 of the grinding wheel.

As best shown in Fig. 3 one of the members of the clamp 58 has hubs 78 and the other member has a hub 80. These three hubs are in alignment and are mounted upon a tubular pivot or sleeve 82. Rotatively and 80 longitudinally shiftable in the sleeve 82 is the shank 84 of the gage device, one end of said shank having a head 86 formed or provided with two shoulders 88-90. At the other end of the shank is a stop 92 which is 85 preferably adjustable relatively to the shank. Said stop may consist of the head of a screw tapped into the end of the shank 84.

The object of this gage is to locate the templet and knife in proper relation to each 90 other and to the clamp. The two shoulders 88-90 are spaced so that when the templet 54 bears against the shoulder 90 and the knife blade 56 bears against the shoulder 88, the said templet and knife blade will be so 95 related that when said gage has been shifted out of the way to the position indicated in Fig. 2 and the edge of the templet 54 is caused to bear against the guide 64 the edge of the knife blade will then be in proper position to be accurately ground.

The object of the stop 92 is to enable the templet and blade to be properly positioned in the clamp. If it be assumed that the thumb screw 62 is loosened sufficiently to enable the templet and blade to be shifted longitudinally relatively to the clamp members, and if the gage is then shifted lengthwise until the stop 92 contacts with the end of the sleeve 82 or hub of the clamp, the gage 110 head 86 will then be at the proper distance longitudinally of the clamp to provide for the proper relative locations of the templet and blade in the manner above described.

Having described my invention, what I 115 claim as new and desire to secure by Letters Patent of the United States is:

1. In a grinding machine, a grinding wheel, a plurality of extended rests for a knife whose edge is to be ground, said rests 120 so located with respect to the grinding wheel as to constitute guides over which may be moved separated points of the knife to be ground and which determine the bevel at which the edge will be ground, and means 125 for determining the extent of approach of the blade towards the grinding wheel in its movement over the guides to impart the desired shape to the cutting edge.

2. In a grinding machine for grinding 130

curved blades, a grinding wheel, a curved guide crossing the periphery of the grinding wheel to serve as a support for the blade near its cutting edge, another guide more remote from the grinding wheel and adapted to be associated with a different portion of the blade, means for adjusting the latter guide to thereby determine the bevel at which the knife will be ground, and means for controlling the movement of the blade towards or from the periphery of the wheel as the blade is moved along the guides.

3. In a grinding machine, a grinding wheel, a support adjustably mounted relatively to said grinding wheel, a plurality of guides mounted on said support to co-operate with longitudinally separated points of a knife blade, one of said guides being adjustable relatively to the other guide thereby to determine the bevel at which the knife will be ground.

4. In a grinding machine, a guide rest serving as a support to position a blade relative to the grinding wheel, a templet mechanically connected to said blade, and a rotatable templet guide associated with said templet to thereby determine the shape of the edge of the blade.

5. In a blade grinding machine, a grinding wheel, spaced blade supporting members associated therewith, a templet having a cross-sectional contour like the cross-sectional contour of the blade to be ground, means for clamping said templet to said blade, and a templet guide resiliently urged against said blade between said points of support and adapted to co-operate with the edge of said templet to determine the movement of the blade toward and away from the grinding wheel to thereby determine the shape of the edge of the blade.

6. In a blade grinding machine, in combination, a grinding wheel, blade guiding means mounted adjacent the periphery of the wheel, a templet constructed and arranged for clamping engagement with a blade to be ground, a support for the blade guiding means, and a templet guide pivoted to the support.

7. In a grinding machine, a grinding wheel, a support, a guide mounted on said support and positioned relatively close to said grinding wheel, a second guide adjustably mounted on said support and adapted to be positioned at a point more remote from said grinding wheel, and a templet guide pivotally mounted upon the support and spring-pressed toward said first mentioned guides in a position between the same.

8. In a blade grinding machine, a grinding wheel, a guide mounted adjacent said grinding wheel, an edge templet adapted to be clamped to the upper surface of a blade to be ground, and a rotatable templet guide pivotally mounted adjacent said blade guide

and spring-pressed toward the same to bear against the upper surface of the blade and the edge of the templet.

9. In a blade grinding machine, a grinding wheel, a guide, a templet, and a clamp constructed and arranged to hold the templet and a blade to be ground in operative relation and to cooperate with said guide to limit the movement of the blade relatively to the grinding wheel, said clamp comprising two pivotally joined members having hooked ends to engage the edges of the templet and blade, and means for adjusting said members relatively to each other to vary the distance between their hooked portions.

10. In a blade grinding machine, in combination, an abrading member, a templet, a templet guide, a clamp for securing the templet to the blade to be ground, and a gage member connected to the clamp and having means to locate the edge of the blade in such relation to the templet that the blade will engage the abrading member when the templet engages the guide.

11. In a blade grinding machine, in combination, an abrading member, a templet, a templet guide, and a gage member having shoulders for engaging the edges of the blade and the templet to locate the blade for grinding.

12. A work and templet holding clamp for grinding machines comprising two hook members pivotally connected together and having a gage member constructed and arranged to define the operative positions of the work and templet relatively to each other and to the clamp.

13. A work and templet holding clamp for grinding machines comprising two members having marginal portions shaped to engage edge portions of the work and templet, a tubular pivot connecting said members together, means for adjusting the angular relationship of said members, and a gage member mounted in said tubular pivot.

14. A work and templet holding clamp for grinding machines comprising two members having marginal portions shaped to engage edge portions of the work and templet, a tubular pivot connecting said members together, means for adjusting the angular relationship of said members, and a gage member having a shank longitudinally movable in said tubular pivot and having shoulders to define the operative positions of the work and templet.

15. A knife grinding machine having, in combination, a grinding wheel, a clamp comprising two hook members, a tubular pivot connecting said members, means for adjusting the angular relationship of said members, and a gage comprising a shank mounted in said tubular pivot and having a stop at one end and means at the other end for defining the position of a knife to be ground.

16. A knife grinding machine having, in combination, a grinding wheel, a clamp comprising two hook members, a tubular pivot connecting said members, means for adjusting the angular relationship of said members, and a gage comprising a shank mounted in said tubular pivot and having

an adjustable stop at one end and a head at the other end provided with shoulders to engage the edges of a templet and a knife 10 to be ground.

In testimony whereof I have signed my name to this specification.

LOUIS A. CASGRAIN.
